UNITED STATES PATENT OFFICE.

LOUIS H. STEAN, OF SHAFTER, NEVADA.

RAILWAY-DISPATCH-ORDER SUPPORT.

1,424,529.

Specification of Letters Patent. Patented Aug. 1, 1922.

Application filed June 18, 1921. Serial No. 478,631.

To all whom it may concern:

Be it known that I, LOUIS H. STEAN, citizen of the United States, residing at Shafter, in the county of Elko and State of Nevada, have invented certain new and useful Improvements in Railway-Dispatch-Order Supports, of which the following is a specification.

The invention relates to improvements in a device for holding train dispatch orders and the like.

It is an object of the invention to provide a device for holding train dispatch orders which can be cheaply manufactured, and can be installed along any railroad line. Although the device is inexpensive to manufacture, it possesses considerable durability and is exceedingly simple to operate. It is a further object of the invention to provide a holder for train dispatch orders, which is positioned adjacent a railway road track and is positioned to receive and support train orders, so that they can be grasped by a trainman on a passing locomotive without lessening the speed of travel of the locomotive.

The invention more specifically comprehends an order holding device which is mounted so that when the same is not in use it can be lowered so the upper surface thereof can lie flush with the road surface, but one which is of such a construction as to permit the order holding portion to be expeditiously raised and placed in such a position as to enable orders to be readily grasped by a passing train.

The invention comprises other novel features of construction, as will more fully hereinafter appear in the accompanying specification. In the drawings forming a part of this application I have disclosed a specific embodiment of the invention, but this disclosure is made for the purpose of illustration, and many changes can be made in the construction and arrangement of the parts of my device.

In the drawings, Figure 1 represents a view of the dispatch holder elevated and in operative position. Figure 2 is a view of the device lowered; and, Figure 3 is a sectional view through the receiving box.

Referring now more particularly to the drawings wherein like reference characters indicate corresponding parts, the numeral 1 designates the base of my device which is preferably mounted below the surface of the

ground adjacent a railway track. Extending from this base is a hollow tube 2, which tube terminates at a point slightly below the surface of the ground. The tube, as clearly shown in the drawings, preferably extends through a bottom portion of the receptacle or box 3 seated in the ground and constituting a receiver for the order holding portion of the device when the same is in a lowered position as will more fully herein-after appear.

Slidably mounted within the hollow tube 2 is a standard 4 telescoping in said tube and having in its upper end offset hook portions 5 which are adapted to constitute supports for lanterns, lights, or the like. Extending at right angles to the standard 4 at the upper end thereof is a cross piece 6 having suitable hooks 7 at each end adapted to receive loops 8 which are fashioned to support dispatch orders when the device is in operation so that said orders can be grasped by a passing trainman without the necessity of bringing the train to a slowdown or stop.

When the device is in use, the standard 4 is raised to the position shown in Figure 1, and the set screw 9 tightened to hold the device in such a position. Orders are placed within one or both of the loops 8 and a cross piece 6 swung around to a position wherein it extends at right angles to the track. A trainman on a passing train is thereby enabled to grasp the dispatch orders contained in one of the loops without requiring the engineer to materially lessen the speed of the train.

When train orders are not placed within the loops 8 and the device is not in active use, then the cross piece 6 can be swung to a position parallel with the tracks whereupon the device will not be in the way, but on the other hand can act as a light or signal support as the occasion may require. I have, however, found it desirable in some instances to lower the upper portion of the device when the same is not in use and to this end the box or receptacle 3 has a pair of cover sections 10 and 11 hinged along each side of the box and disconnected at their meeting edges. Near the meeting edges of these cover sections I have provided slight cutout portions for the passage of the standard 4. If it is desired to lower the standard, then the cover sections 10 and 11 are raised and the set screw 9 loosened and the standard thereby falls downwardly, the

cross piece 6 and the loops 8 being seated within the receptacle 3, whereupon the closure sections 10 and 11 are lowered thus closing and protecting the movable portion 5 of the dispatch holding device. By thus constructing the receptacle there are no dangerous depressions along the track bed as the surfaces of the closure lie flush with the surface of the earth adjacent the track.

10 Any convenient means may be used for holding the dispatch orders by the loops 8, but I preferably employ spring fingers 12 for this purpose, such fingers merely engaging the track orders with sufficient firmness 15 to hold them in position, but offering no resistance when they are grasped by a trainman.

Having thus described the invention, what I claim is:

20 1. A train dispatch order holding device comprising an upstanding part adapted to be placed beneath a road surface, a standard slidably connected therewith, a cross arm carried by said standard, a train dispatch order holding device supported by the cross arm, and means for maintaining said standard in a raised position, said means permitting the standard to be rotated to move the cross arm to a position at right angles to the 25 track or parallel therewith.

30 2. A dispatch order holding device comprising a portion adapted to be positioned beneath a road surface, a receptacle into which the upper end of said portion terminates, a standard slidably cooperating with the said portion, a cross arm carried by the upper end of said standard, a dispatch holding device supported by said cross arm, means for maintaining the standard in a 35 raised position, said standard being adapted to be lowered when not in use to a position whereby the train dispatch holding means is confined within the receptacle.

35 4. A dispatch order holding device comprising a base portion adapted to be positioned beneath a road surface, a receptacle into which the upper end of said portion terminates, a standard telescoping with said base, a cross arm carried by said standard, a dispatch holding device supported by the cross arm, means for maintaining the standard in a raised position, said standard being adapted to be lowered when not in use to a 40 position within the receptacle, and closures 45 for said receptacle lying flush with the road surface.

50 5. A train dispatch order holding device comprising an elongated upstanding part adapted to be buried in the earth adjacent a railroad track, a slidable standard con-

nected therewith and adapted to lie in a lowered position when the device is out of operation so that the upper end thereof does not extend materially beyond the road surface, a cross arm carried by said standard, 65 train dispatch holding devices supported on said cross arm, and adjustable means for maintaining said standard in an elevated position materially beyond the road surface when a dispatch is to be transmitted to a 70 passing train.

5. A train dispatch order holding device comprising an elongated upstanding part adapted to be buried in the earth adjacent a railroad track, a slidable standard connected therewith and adapted to lie in a lowered position when the device is out of operation so that the upper end thereof does not extend materially beyond the road surface, a cross arm carried by said standard, train 75 dispatch holding devices supported on said cross arm, and adjustable means for maintaining said standard in an elevated position materially beyond the road surface when a dispatch is to be transmitted to a passing train, a receptacle seated within a depression in the road surface adapted to house the cross arm and the dispatch holders when in a lowered position, and hinged closures for 80 said receptacle.

6. A train dispatch order holding device comprising a vertical part adapted to be embedded beneath a road surface, a telescopic standard carried thereby, means for holding said standard in a raised position whereby 95 the upper end is materially above the road surface, a cross arm carried by the standard, dispatch holders mounted on said cross arm, said standard being adapted when in an inoperative position to be lowered whereby 100 the upper edge is substantially flush with the road surface.

7. A train dispatch order holding device comprising a vertical part adapted to be embedded beneath a road surface, a telescopic 105 standard carried thereby, means for holding said standard in a raised position whereby the upper end is materially above the road surface, a cross arm carried by the standard, dispatch holders mounted on said cross arm, 110 said standard being adapted when in an inoperative position to be lowered whereby the upper edge is substantially flush with the road surface, and housing means seated within a pocket in said road surface for 115 enclosing the cross arm and its dispatch holders when in a lowered position.

In testimony whereof I affix my signature.

LOUIS H. STEAN.
